DEAD BOLT LATCH

Irving J. Fletcher, New Britain, Conn., assignor
to The American Hardware Corporation, New
Britain, Conn., a corporation of Connecticut

Application August 11, 1949, Serial No. 109,688

15 Claims. (Cl. 292—61)

1

This invention relates to a dead bolt latch and more particularly to a latch in which the latching bolt, when in latching position, automatically becomes inoperative so that it may not be moved into unlatched position except by operation of the operating member which is provided therefor.

It is well known to those skilled in the art that dead bolt latches commonly contain a latching bolt and a separate auxiliary bolt which operates a mechanism for rendering the latching bolt immovable after it has moved into latching position. Such latches, however, have been complicated in construction and, therefore, expensive to manufacture.

An object of this invention is to provide a lock having a latching bolt which is normally immovable to a retracted position, except by operation of the operating member provided therefor, and which becomes operable independently of said operating member upon being rotated by engagement with a cooperating striker plate that is associated with a door on which the said latch is used.

A further object of this invention is to provide a latch in which the latching bolt thereof becomes immovable, when the same is in latching position, so that it may not be forced back into unlocked position by manipulation of the bolt from the exterior of the latch.

A further object is the provision of suitable and effective means for preventing rotation of the latching bolt, when in latching position, so that it may not be forced back into unlatched position.

A still further object of this invention is to provide a dead bolt lock having novel features not heretofore provided in such locks and which is durable in construction and may be economically manufactured.

Further objects and advantages of this invention will be more clearly understood from the following description and the accompanying drawings in which:

Fig. 1 is a plan view of my improved latch showing the same attached to a door and with the casing thereof shown in central horizontal section.

Fig. 2 is a sectional end view thereof on line 2—2 of Fig. 1.

Fig. 3 is a rear view of the said latch partly in central vertical section.

Fig. 4 is an exterior end view of the latch and a portion of the door to which it is attached.

Fig. 5 is a view similar to Fig. 3 but showing the latch in a retracted or unlatched position.

2

Fig. 6 is a sectional end view on line 6—6 of Fig. 1.

Fig. 7 is a sectional end view on line 7—7 of Fig. 5.

Fig. 8 is a plan view, partly in section, showing the operation of my improved latch as it is moved towards latching position.

Fig. 9 is an end view thereof on line 9—9 of Fig. 8.

Fig. 10 is a plan view, similar to Fig. 8, but showing the different position during the operation of the latch.

Fig. 11 is a reduced diagrammatic end view of the striker plate and latching bolt in the relative position illustrated in Fig. 8.

Fig. 12 is a similar view with the parts in the relative position illustrated in Fig. 10.

Fig. 13 is a reduced diagrammatic end view showing a modified form of striker plate and latching bolt.

Fig. 14 is a similar view showing the latching bolt in a different position.

In the preferred form illustrated in the drawings, my improved latch comprises a tubular casing 5 which has secured thereto a fastening plate including a main plate 6 that is secured to the exterior of the casing, at the end thereof, and an auxiliary plate 7 which is secured to the plate 6 and extends over the end of the casing for the purpose hereinafter described.

The mechanism of my improved latch comprises a latching bolt having a head portion 8 which is slidable in the tubular casing 5. A stem 9 extends from said head portion through a backing plate 10 that is disposed within the said casing and positioned therein by means of posts 11—11 which extend from a supporting block consisting of two opposed halves 12—12 that are secured to the casing 5 by means of a positioning pin 13.

The said backing plate 10 is secured to the posts 11—11 by means of notches 14 which receive reduced portions within grooves 15 in each of said posts.

A combined compression and torsion latching bolt spring member 16 is provided between the head portion 8 and the backing plate 10 for normally urging the said latching bolt in an outward direction from the casing and into its latching position; the said spring being secured against rotation relatively to the backing plate 10 by means of a hooked end portion 17 and relatively to the latching bolt by means of an inwardly projecting end portion 18 which extends into a hole in the shank 9.

A pair of opposed bolt operating yokes 19—19

are slidably mounted upon the posts 11-11 and each of said yokes has a pair of opposed operating bars 20-20 which are spaced apart and extend rearwardly therefrom. The said operating bars are each provided at their inner ends with laterally extending hook portions 21 which engage opposite sides of a pair of roll backs 22-22, each of which is secured to the adjacent end portions of an operating spindle which extends from opposite sides of the door and may be formed of two separate sections 23-23 to permit rotation of one portion of the spindle independently of the other; each of said sections being provided with a conventional operating knob.

On each of the posts 11-11 there is provided a compression spring 24 which is disposed between the block formed by the halves 12-12 and one of the yoke members 19 and urges the said members into their normal position wherein the latching bolt is permitted to be moved into latching position under the tension of the spring member 16.

A pair of blocking levers 25-25 are pivotally mounted at 26-26, between opposed inwardly extending portions on the block halves 12-12, and extend forwardly from said pivotal points with their free ends 25-b-25-b providing obstructions normally in the path of movement of radial projections 27-27 which form detents on the latching bolt stem 9. Each of said levers 25-25 has an extension 26-a with a cam portion thereon that is engaged by a spreader roller 28 mounted between the related pair of opposed operative bars 20-20. The said levers are urged towards normal position and into engagement with the said rolls by means of a spring member 29 having leg portions fitting into notches in the said levers, as shown, for urging the extensions 26-a outwardly and thereby normally retaining the free ends 25-b-25-b of the levers 25-25 in the path of the radial projections 27-27 on the shank 9.

The fastening plate portion 1 is provided with an irregular opening having a circular portion 31 and an inwardly projecting stop portion 31 which engages a flattened surface 32 on the back of the bolt, to limit rotation of the bolt under the influence of the spring member 16, and overlies a stop shoulder 33, formed by said flattened surface inwardly of the circumferential surface of the portion 34 on the head of said bolt to limit movement of the bolt towards latching position also under the influence of the said spring member. The front portion of the said bolt is provided with a bevelled cam surface 35 that is flattened on an angle to the longitudinal axis of the bolt and to the normally vertical plane passing through the axis thereof so as to provide a cam surface for both rotating the bolt and forcing it rearwardly towards retracted position as will be hereinafter described.

In the preferred form illustrated, my lock is used in combination with a striker plate 36 which is secured to the frame 37 of the door and has a portion 38 extending therefrom and curved backwardly from the door, as indicated at 39, to cooperate with the cam surface 35 of the locking bolt for retracting it as illustrated in Fig. 8.

The said striker plate is provided with a hole 40 having a straight edge portion 41 which engages the flat surface 32 of the latching bolt, when the said latching bolt is in latching posi-

tion within the said hole 40, and prevents rotation thereof.

In the modified form illustrated in Figs. 13 and 14, the disposition of the cam surface 35 on an angle to the said normally vertical plane is omitted and, instead, the said surface is made at an angle only to the axis of the bolt and parallel to the said normally vertical plane, as shown at 35-a, and the projection 38-a of the striker plate 37-a extends outwardly and backwardly therefrom on an angle to the vertical axis of the bolt.

Such locks of the type herein described are commonly provided with key operated means for preventing operation of the spindle 23 for drawing the latching bolt back into unlocked position. Such key operated means may be of conventional form and may operate to lock the said spindle 23 in any suitable manner well known to those skilled in the art and are not, therefore, shown in the drawings.

The operation of my improved lock is as follows:

When the latch is in the latched position, as illustrated in Fig. 3, the latching bolt 8 projects through the opening 40 in the striker plate 36 and locks the door in closed position.

Assuming that the spindle 23 is locked by the key operated means; the latching bolt cannot be withdrawn into the casing 5 so as to unlock the door. Upon the said key controlled means being operated to release the spindle 23, the said spindle may be rotated in either direction whereupon one of the roll back members 22 will engage the projections 21 on a pair of the yoke bars 20 and thereby draw rearwardly an operating yoke 19 which is connected to the locking bolt by means of the projections 27-27. This will cause the spreader rollers 28 to operate the levers 25-25 and thereby spread them, to the position shown in Fig. 5, wherein the obstructing ends thereof will be out of the path of the projections 27-27 and thereby permit the said yoke member 19 to withdraw the bolt into unlatched position, as illustrated in Fig. 5. It will therefore be understood that, when the lock is operated by the rotation of the spindle 23, the levers 25-25 are spread apart, against the tension of the spring 29, so as to permit the bolt to be drawn back into retracted position.

When the door is to be moved from an open to a closed position, it is required that the latching bolt 8 be retracted into the casing 5 to permit the door to close. This is permitted by the latching bolt being first rotated so that the projections 27-27 on the bolt will avoid the obstructing ends of the levers 25-25.

The bolt is rotated upon engagement of the angularly disposed cam surface 35 thereof with the backwardly curved portion 39 of the striker plate, as illustrated in Figs. 8, 11 and 12. When the said cam surface strikes the end of the curved portion 39, the bolt will be rotated, from the position shown in Fig. 11 to that shown in Fig. 12, so that the said projections will be in the position shown in Fig. 9 and out of alignment with the ends of the levers 25-25.

As the door continues to move towards closed position, the bolt will be forced inwardly by means of the angle in the surface 35. This will cause the spring 16 to become compressed and, at the same time, torsioned by the rotation of the bolt until the said bolt reaches the position illustrated in Fig. 10. In this position, the bolt will be in contact with the surface of the striker

plate 36 only at the high point indicated at 42 which is formed by tapering the end surface of the bolt outwardly and downwardly from the longitudinal axis thereof and which will act as a fulcrum to thereby permit rotation of the bolt with a minimum of friction so that it will be quickly rotated in a reversed direction, by the unwinding action of the spring 16, towards its normal position illustrated in Fig. 4. When in this position, the bolt will be positioned by means of the engagement between the flat surface 32 and the edge of the projection 31 in the hole in the auxiliary plate 7. As the door reaches its fully closed position, the bolt will be in alignment with the opening 40 in the striker plate 36 and will be moved by the expansion of the spring 16 so that it is projected outwardly from the casing 5 and into said opening.

During this movement of the latching bolt, the projections 27-27 will engage the cam surfaces 25-a-25-a on the blocking levers and spread said levers apart to permit the said projections to move with the bolt past the obstructing portions of the levers.

It will be noted that the inward movement of the bolt caused by the striker plate is resisted only by the spring member 16 which is backed by the plate 10, and that no action is applied against the springs 24 during such movement. This permits a much desired easy action on the bolt when it is retracted by engagement with the striker plate and not by the operation of the spindle 23.

When the bolt is returned into latching position within the opening 40, the rotation of said bolt is prevented by engagement between the flat surface 32 and the straight surface 41 at the side of the hole 40. This will prevent manipulation of the bolt by an unauthorized person, who may attempt to rotate the bolt with an improvised tool, so as to force it back into unlatched position, since the bolt cannot be moved back without being first rotated because the projections 27-27 would strike the obstructing ends of the blocking levers 25-25. It will, therefore, be noted that the bolt of my improved latch cannot be moved to unlocking position by tampering with the bolt through the space between the door and the door frame since the said bolt cannot be rotated while in latched position and, therefore, cannot be forced back into unlatched position. This is an important element of my invention.

It will also be noted that a very important feature is provided in my improved latch through the application of a light pressure by the spring 16 against the retraction of the latching bolt by the striker plate and a heavier pressure against the operation of the bolt by means of the knob spindles 23. This feature is highly desired in lock constructions since it permits light operation of the bolt by the striker plate, so that the door will be permitted to close easily, and a stiffer operation of the bolt by rotation of the knob spindle so that the said spindle will be more readily returned to its normal position upon being released.

From the above description, it will be clearly understood that I have provided a novel dead bolt latch in which the latching bolt cannot be forced back into unlatched position without first being rotated and which cannot be so rotated while the door is in closed position.

I claim:

1. A latch mechanism comprising a latching

bolt, a striker plate to receive said bolt when in latching position, means for preventing movement of said bolt to an unlatched position, the said means being operable upon rotation of the bolt to permit movement thereof to an unlatched position, and cooperating means on said plate and bolt for preventing rotation of the bolt when in latched position.

2. A latch mechanism including a latching bolt, 10 a striker plate to receive said bolt, means for preventing movement of the bolt to an unlatched position, said means being operable upon rotation of the bolt to permit movement thereof to an unlatched position, the said bolt having a straight surface thereon, and means on said striker plate cooperating with said straight surface for preventing rotation of the bolt when in latched position.

3. A latch mechanism including a latching bolt, 20 means for preventing movement of the bolt into unlatched position, the said means being operable upon rotation of the bolt to permit movement thereof to an unlatched position, a striker plate for receiving said bolt, a cam surface on said bolt angularly disposed relatively to the vertical axis thereof for rotating the bolt upon engagement with the said striker plate, and a flat surface on said bolt engageable with a cooperating portion of said striker plate for preventing rotation of the bolt when in latched position.

4. In a latching mechanism, the combination 30 of a casing, a latching bolt normally projecting outwardly from said casing into latching position and retractable thereinto, means for preventing movement of said bolt to retracted position; said means being operable upon rotation of the bolt to permit movement thereof to its retracted position, and a striker plate for receiving said bolt when in latching position; the said bolt having a surface disposed for rotating and retracting it upon engagement with the striker plate and a surface engageable with a cooperating portion on said striker plate for preventing rotation of the bolt when in latched position.

5. A latch mechanism including a casing, a 40 rotatable latching bolt normally projecting from said casing into latching position and retractable therein into unlatched position, a striker plate, movable blocking means in the path of the bolt for preventing retraction thereof, cooperative means on said striker plate and said bolt for rotating the bolt, the said blocking means permitting retraction of the bolt upon rotation thereof, manually operable means for retracting said bolt, said manually operable means including a spindle, a roll back member on said spindle, a yoke operable by said roll back member, means connecting said bolt to said yoke for retracting the bolt upon rotation of the spindle, and means operable upon movement of said yoke to move said blocking means from the path of the bolt and to thereby permit retraction of the bolt.

6. A latch mechanism including a casing, a 50 latching bolt normally projecting from said casing into latching position and retractable therein into unlatched position, a detent on the end of said bolt, a blocking member in the path of the bolt engageable with said detent to prevent retraction of the bolt, the said detent being movable upon rotation of the bolt to avoid the said blocking member and permit retraction of the bolt, manually operable means for retracting the bolt, and means operable upon the operation of the manually operable means for moving said

blocking member out of the path of the detent to permit retraction of the bolt.

7. A latch mechanism including a casing, a latching bolt normally projecting from said casing into latching position and retractable therein into unlatched position, a detent on said bolt, a blocking member having an obstructing portion engageable with said detent to prevent retraction of the bolt, means for rotating the bolt to cause said detent to avoid the obstructing portion and permit retraction of the bolt, means for retracting the bolt upon the rotation thereof, manually operable means for retracting the bolt independently of the first-mentioned retracting means, means operable upon the operation of the manually operable means for moving the said obstructing portion out of the path of the detent to permit retraction of the bolt, and separate means operable to remove the said obstructing portion from the path of said detent and thereby permit the return of the bolt to latching position.

8. A latch comprising a casing, a bolt slideable in said casing into latching and retracted position, a stem extended from said bolt, a detent projecting from said stem, a blocking lever pivotally mounted in said casing and having an obstructing portion normally positioned in the path of said detent to prevent retraction of the bolt, a spring urging said lever into normal position, a manually operable member, means actuated upon the operation of said member including an operating yoke for drawing the bolt into retracted position, and means movable with said yoke for rocking the lever against the tension of said spring to move the said obstructing portion out of the path of the detent and thereby permit retraction of the bolt.

9. A latch comprising a casing, a latching bolt normally projecting from said casing into latching position and retractable therein into unlatched position, a fastening plate connected to the end of said casing and having an opening therein through which the bolt projects, stop means on the bolt engageable with said plate to position the bolt in latching position, means requiring rotation of the bolt to permit retraction thereof into unlatched position, means for rotating the bolt in one direction to permit retraction thereof, a spring member for rotating the bolt in an opposite direction to return it towards latching position, and an abutment in said opening engageable with a portion of the bolt for locating it in latching position.

10. A latch comprising a casing, a bolt slideable in said casing into latching and retracted positions, means for preventing retraction of said bolt, the said means being operable upon rotation of the bolt to permit retraction thereof, a spring member yieldingly urging said bolt into latching position, a striker plate having an opening therein to receive said bolt when in latching position, cooperating means on said bolt and striker plate for rotating the bolt and then retracting it, and a high point upon the end of said bolt engageable with the surface of said plate to provide a turning point for minimizing friction in the rotation of the bolt toward latching position.

11. A latch comprising a latching bolt normally extending from a casing in latching position, means resiliently urging said bolt into latching position, a striker plate having an opening therein to receive said bolt when in latching position, means for preventing retraction of the bolt, said means being operable upon rotation of the bolt to per-

mit retraction thereof, a spring yieldingly resisting retraction and rotation of the bolt, a cam surface on said bolt engageable with the striker plate for rotating and retracting the bolt against the tension of said spring, a flat surface on said bolt engageable with a corresponding portion of the wall of the opening in the striker plate to prevent rotation of the bolt when in latching position, and a high point upon the end of said bolt engageable with the surface of the striker plate, after the bolt has been rotated in one direction and retracted, to minimize friction in the rotation of the bolt in the opposite direction and thereby permit the return of the bolt into latching position under the tension of said spring.

12. A latch comprising a casing, a bolt slideable in said casing and including a head portion and a stem portion, a fastening plate secured to an end of said casing and having an opening therein through which the head of the bolt projects in latching position, means normally urging the said head into latching position, cooperating stop means on said bolt and plate for locating the bolt in said latching position, a backing plate having an opening therein slidably receiving the said stem, a spring member between said backing plate and head of the bolt rotatably and slidably urging the bolt towards latching position, projections on said stem portion, a pair of levers having abutment portions normally positioned for engagement with said projections to prevent retraction of the bolt, spring means for urging said levers to normally position said abutment portions, manually operable means including a rotatable spindle, a yoke engageable with said projections, a roll-back member on said spindle for operating said yoke for drawing said bolt into retracted position, cooperating cam means on said yoke and levers for separating the abutment portions against the tension of the spring means to thereby remove said portions from the path of the projections to permit retraction of the bolt upon the rotation of said spindle, spring means normally urging the yoke to cause return of the bolt to latching position under the tension of the said spring member, cooperating cam means on said bolt and striker plate for rotating the bolt and then retracting it independently of the said manually operable spindle, cooperating means in said bolt head and striker plate to prevent rotation of the bolt when in latching position, and a high point on said bolt engageable with the surface of said surface striker plate, after the retraction thereof, to minimize friction in the rotation of the bolt towards its normal position.

13. A latch comprising a casing, a fastening plate secured to the end of said casing and having an opening therein, a bolt slideable in said casing and having a head normally projecting through said opening, cooperating stop means on said plate and head for locating the bolt in latching position, a spring normally urging the bolt into said latching position, a stem projecting from said head, projections on said stem, a spring rotatably and slidably urging the bolt towards its latching position, a block secured to said casing, a pair of blocking levers pivoted on said block and having obstructing portions normally disposed in the path of movement of said projections to prevent retraction of the bolt, a spindle rotatable in said block, roll-back members on said spindle, a yoke operable by said members for drawing the bolt into retracted position, cam means on said levers, rollers on said

yoke engageable with said cam means for rocking the levers to move the obstructing portions out of the path of the projections upon the rotation of the spindle and thereby permit retraction of the bolt, supporting posts extending from said block, a backing plate positioned by said posts, springs on said posts resiliently urging the yoke towards normal position to permit the return of the bolt to latching position under the tension of the first-mentioned spring member, a striker plate having an opening therein adapted to receive said bolt when in latching position, cooperating cam means on said bolt and striker plate for rotating said bolt to cause the said projections to avoid the said obstructing portions of the levers and then retract the said bolt against the tension of the spring member, a high point upon the end of said bolt head to minimize friction and permit rotation of the bolt towards latching position, and cooperating means on said striker plate and bolt to prevent rotation of the bolt when in latching position.

14. A latch comprising the mechanism set

forth in claim 13 and including cam means engageable by the projections to move the obstructing portions out of the path of said projections and permit the return of the latching bolt to its latching position.

15. A latch mechanism comprising a latch bolt, means engageable with said bolt for preventing depression thereof; the said means being adapted, upon rotation of the bolt, to permit depression thereof to unlatched position and means on the bolt and forming an integral part thereof for preventing rotation thereof when in latched position.

IRVING J. FLETCHIER.
